PREFABRICATED GARMENT CONSTRUCTION AND METHOD THEREFOR

Louis Becker, Brooklyn, N. Y.

Application October 24, 1950, Serial No. 191,845

1 Claim. (Cl. 2—243)

1 This invention relates to garments such as ladies' outer apparel. It is particularly directed to a set of prefabricated complementary garment parts or sections, pre-cut to pattern and ready to be sewn together, and having all sundries and items included and designated for the completion of a finished garment.

Various attempts have been made in the past to obviate the difficulties of sewing at home, so as to produce a practical garment which is correctly patterned and economically cut and properly fashioned. The average home sewer uses a dummy or figure on which the proposed garment is draped, spending thereby considerable time in experimentation and guess work, resulting as a rule in a great waste of material. Such garments produced by so called "home dress making" lack such advantages as would be obtained by expert specialists in the styling and pattern making fields, resulting in garments which have a "home made look."

It has been suggested, in order to overcome these disadvantages, that an illustrated pattern accompany the fabric, but this left the method of fabricating or cutting the fabric and completing the garment to persons who lack sufficient experience in cutting the indicated parts and properly joining them.

It has also been suggested that the fabric be marked or printed, indicating the pattern thereon. This method however left much to error since $\frac{1}{8}$ " deviation would be sufficient to cause inaccuracy of fit. The average grading of sizes requires but $\frac{1}{8}$ " to $\frac{1}{4}$ " additional to be added to the edge.

It is therefore an object of my invention to provide a set of complementary pre-cut garment pieces which will obviate the disadvantages noted above, and to enable the average home-sewer to have the means of completing the garment in a professional manner having all the necessary embroideries, tuckings, buttons and other sundries made part of the prefabricated garment. It is hence a further object of the present invention to furnish to the home sewer a set of pre-cut garment parts which are easy to stitch together to complete the garment.

Another object of this invention is to simplify the identification of the edges of the pre-cut component parts of the garment which are to be stitched or joined together.

A further object of this invention is to provide a set of prefabricated garment parts so constructed that there is least waste of material and said parts being provided with means to indicate to

2 the sewer in such a way that it would be hard to mistake how the parts are to be stitched together. The various pre-cut parts may be attractively packaged together in a box on which may be printed a picture of the finished garment so as to help the sewer in completing the garment.

Yet another object of this invention is to provide a highly improved set of pre-cut garment cloth parts, embodying the invention, which shall be relatively inexpensive to manufacture and which shall yet be practical and efficient to a high degree.

Other objects of this invention will in part be obvious and in part hereinafter pointed out.

15 The invention accordingly consists in the features of construction, combinations of elements, and arrangement of parts, which will be exemplified in the construction hereinafter described, and of which the scope of invention will be indicated in the following claim.

In the accompanying drawings in which is shown various illustrative embodiments of this invention,

15 Fig. 1 is a rear perspective view of a completed garment made of pre-cut component parts, embodying the invention;

20 Fig. 2 is a front perspective view of the figure shown in Fig. 1; and

25 Fig. 3 is a top plan view of a set of complementary component cloth parts, pre-cut and embodying the invention, being provided with means to indicate which edges of various component parts are to be stitched together, said component parts when stitched together forming the garment shown in Figs. 1 and 2.

30 Referring now in detail to the drawing, 10 designates a completed garment stitched together from the set of pre-cut component cloth parts shown in Fig. 3 and embodying the invention. The garment 10 is merely shown for the purpose of illustration, it being understood that the invention may be applied to any suitable garment. The garment 10 is a bolero and is but one of many garments which may be made by pre-cut cloth parts embodying the invention.

35 The garment 10 comprises a pair of symmetrical bolero back and sleeve sections B, B', a pair of symmetrical bolero sleeve front sections A, A', a pair of symmetrical front facing parts D, D', a back neck facing part E, a pair of symmetrical lower back facing parts F, F', and a pair of symmetrical sleeve facing parts G, G', and monogram or insignia already embroidered on part of bolero.

40 45 50 55 The sections B, B' are substantially similar

and symmetrically disposed. Said sections B, B' comprise edges 11, 11' respectively, which are co-extensive and are to be stitched together. Extending from the edges 11, 11' are similar rectangular projections 12, 12'. These extensions 12, 12' may be made by punching them through with a die, or in any other suitable manner. The extensions are similar in shape so that the person who sews the various parts or sections shown in Fig. 3 to form the garment 10 will know that the edges 11, 11' are to be stitched together. The person will know it by matching up the similar rectangular extensions 12, 12' on these two edges.

In practice the extensions 12, 12' are first made, and then the edges 11 may be cut with the usual cloth cutting knives or machines. The cloth may be cut from opposite ends up to the extensions 12, 12'.

The parts B, B' are also formed with corresponding symmetrical neck edges 13, 13' respectively. The parts B, B' also have top sleeve edges 14, 14' respectively, extending from the edges 13, 13' respectively. Said parts B, B' are also formed with end sleeve edges 15, 15' extending from the edges 14, 14'. Said parts B, B' are also formed with lower sleeve and front edges 16, 16' extending from the edges 15, 15' respectively. Said parts B, B' are furthermore formed with longitudinally curved bottom edges 17, 17' respectively, interconnecting the edges 11, 16 and 11', 16' respectively.

The bolero sleeve front parts A, A' are substantially similar and symmetrically disposed with respect to one another. Said parts A, A' are formed with corresponding top sleeve edges 20, 20' respectively. The edge 20 of part A is to be stitched to the edge 14 of part B. For this purpose the parts B and A are formed with similar extensions 21, 21' extending from said edges. The extensions 21, 21' are shown as being semi-circular in shape. They may likewise be punched out with a die before cutting the remainder of the edges 20, 14, with the usual cloth cutting knife or machine. The user will know that the edge 14 is to be stitched to the edge 20 by matching up the similar extensions or tabs 21, 21'. The edge 20' of part A' is to be stitched to the edge 14' of part B', the home sewer will know that these two edges are to be stitched together, by reason of tab extensions 22, 22' extending from the edges 20' and 14' respectively. These tab extensions 22, 22' are in the shape of a double semi-circle. These tabs may likewise be punched out with a die before cutting the edges 20', 14'.

The bolero sleeve front parts A, A' are furthermore formed with end sleeve edges 23, 23' extending from the edges 20, 20' respectively. Extending from the edges 23, 23' are lower sleeve and back edges 24, 24'. The edges 24, 24' may be formed with V-shaped cut-outs 25, 25' and the edges of the cut-outs will be sewn together as will be obvious, although if desired any suitable shaped tabs may be applied to the corresponding edges to indicate that they are to be stitched together.

Extending from the lower ends of the edges 24, 24' are front curved edges 26, 26', and extending from the upper ends of said edges are corresponding neck edges 27, 27'.

The front facing parts D, D' are likewise similar and symmetrically disposed one with respect to the other. They are formed with corresponding outer edges 28, 28'. The edge 28 of part D corresponds to the edge 26 of part A, and is to

be stitched thereto. Extending from said edges 28 and 28 are similar tabs 29, 29' which may be punched out with a die. These tabs are shown to be triple triangles for the purpose of illustration. Extending from the edges 28, 28' are corresponding neck line edges 30, 30'. The neck line 30 of part D is to be stitched to the neck line 27 of part A. Extending from said edges 30, 27 are tabs 31, 31' respectively to indicate that said edges 30 and 27 are to be stitched together. The tabs 31, 31' are similar and are here shown in the form of a trefoil.

The edges 30' and 27' are likewise to be stitched together. Extending from said edges are tabs 32, 32', similar in shape, to indicate that said edges are to be stitched together. The tabs 32, 32' may be in the shape of turrets with three towers. Extending from edges 30, 30' are upper end or rear edges 33, 33'. Extending from said edges 33, 33' are rear edges 34, 34'. The edges 34, 34' are not stitched to anything and have no tabs. Interconnecting the edges 28, 34 and 28', 34' are edges 35, 35' respectively.

The edges 16 and 24 of parts B and A are stitched together. Extending from said edges are similar tabs 36, 36' here shown in the shape of a triangle. These similar tabs indicate that edges 16 and 24 are to be matched up and stitched together.

The edges 16' and 24' of parts B' and A' are to be stitched together. Extending from said edges are tabs 37, 37'. These tabs are similar and are here shown for the purpose of illustration as double triangles, to indicate to the user that the edges 16' and 24' are to be matched up and stitched together.

The edge 35 of part D is to be stitched to the lower end of edge 24 of part A. Said edge 35 has a tab extension 38, and the edge 24 has adjacent its lower end a tab 38' similar to tab 38 to indicate that the edge 35 is to be stitched to the lower end of edge 24. The tabs 38, 38' are so positioned as to indicate the exact place where the edge 35 is to be stitched. In other words, in stitching, the user matches up the tabs 38, 38' so that they register. In fact all the tab extensions of all the parts are so placed that said tabs must register when the matching parts are in exact position coextensively for stitching, so as to avoid any inaccuracy or wrong alignment or registration of edges to be stitched together.

Edge 35' is to be stitched to the lower end of edge 24'. To this end there is a tab extension 39 on the lower end of edge 24' and a corresponding or similar tab 39' on the edge 35'. The two tabs are registered and the edge 35' matched in proper position with relation to the edge 24' and said edges are stitched together.

The edges 28' and 28' of parts D' and A' are to be stitched together. For this reason there extends from edge 28' a tab extension 40 and from edge 28' a similar tab extension 40', indicating that the edges 28' and 28' are to be stitched together.

The back neck facing part E has an inner edge 41, end edges 42 and 43 and a rear or outer edge 44. The inner edge 41 is to be stitched one-half to the edge 13 and one-half to the edge 13'. The edge 13 has a tab 45 and on edge 41 is a tab 45', similar thereto. The tabs 45, 45' are matched up and registered to indicate the exact position of stitching. Extending from edge 13' is a tab 46 and extending from said edge 41 is a tab 46', similar to the tab 46. The tabs 46, 46' are

matched up and registered to indicate which portion of the edge 41 is stitched to the edge 13'. The edge 42 is to be stitched to the edge 33 of part D. Extending from said edges 33 and 42 are similar tabs 47, 47' to indicate that said edges are to be matched up and stitched together. The edges 33' and 43 are to be stitched together and extending from said edges are similar tabs 48, 48', indicating that said edges are to be stitched together.

The lower back facing parts F and F' are formed with upper edges 50, 50'. Extending from the inner ends of the edges 50, 50' are edges 51, 51'. Extending from the edges 51, 51' are lower edges 52, 52' and interconnecting the edges 50, 52 and 50', 52' are edges 53, 53'. The edges 50, 50' are not stitched to anything and have no tab extensions.

The edges 51, 51' are to be stitched together and are formed with tab extensions 54, 54' which are similar and are shown to be dove-tailed shape. The edge 52 of part F is to be stitched to edge 17 of part B. Extending from said edges are shallow elongated rectangular tabs 56, 56' to indicate that these two edges are to be stitched together. The edge 53 is to be stitched to the lower end of edge 16. Extending from the edge 53 is a tab 57 and extending from the lower end of edge 16 is a similar tab 57' to indicate that edge 53 is to be stitched to the lower end of edge 16. The tabs 57, 57' have to be matched up or registered for exact positioning of edge 53 relative to edge 16. The tabs 57, 57' may comprise double pointed shapes for the purpose of illustration.

Edge 52' of part F' is to be stitched to edge 17' of part B'. Extending from edge 52' is a tab 58 and extending from edge 17' is a tab 58'. The tabs 58, 58' are similar to indicate to the home sewer that said edges 52' and 17' are to be stitched together. The edge 53' is to be stitched to the lower end of edge 16'. Extending from edge 53' is a tab 59 and extending from the lower end of edge 16' is a similar tab 59'. The tabs 59, 59' are matched up and registered to indicate to what part of edge 16' edge 53' is to be stitched.

The sleeve facing parts G, G' have corresponding edges 60 and 60'. Extending from the outer ends of edge 60 are end edges 61 formed with similar extending tabs 62 to indicate that said edges 61 are to be stitched together. Interconnecting the edges 61 of part G is an edge 63 parallel to the edge 60. Part of edge 63 is to be stitched to edge 23 of part A and part of said edge 63 is to be stitched to edge 15 of part B. Extending from one part of edge 63 is a tab 64 and extending from edge 23' is a similar tab 64'. The tabs 64, 64' are matched up and registered to indicate what part of edge 63 is to be stitched to edge 23.

Extending from another part of edge 63 is a tab 65 and extending from edge 15 is a tab 65'. The tabs 65, 65' are matched up to indicate what part of edge 63 is to be stitched to edge 15. The tabs 64, 64' may be in the shape of 45° right triangles. The tabs 65, 65' may be in the shape of double towered turrets.

The part G' is similar and symmetrically disposed to the part G. Its edge 60' is not stitched to any other part and has no tab extensions. Extending from the ends of edge 60' are edges 66 formed with similar tab extensions 67 which are matched up, indicating that the edges 66 are to be stitched together. The edges 66 are

interconnected by an edge 68 parallel to the edge 60' and the edge 68 is stitched partly to the edge 23' of part A' and partly to the edge 15' of the part B'.

- 5 Extending from a part of edge 68 is a tab 69 and extending from edge 23' is a similar tab 69'. The tabs 69, 69' are registered to bring edge 23' into registration with part of edge 68 and said edges are stitched together. The placement 10 of the tabs 69, 69' insures the correct positioning of edge 23' with respect to edge 68. Extending from another part of edge 68 is a tab 70 and extending from edge 15' of part B' is a tab 70'. The tabs 70, 70' may be registered or matched up to register edge 15' with a part of edge 68 and said edges are stitched together.

It will be noted that all the tabs may be punched out with a die and that the tabs are all so placed that edges to be stitched may be

- 20 matched up correctly. In other words, the tab on one edge is registered with the tab on the corresponding edge to be stitched to the first edge, to make sure that the two edges to be stitched together are aligned in coextensive relationship. 25 With such construction the user is greatly aided and is prevented from stitching edges together in reverse direction. For this reason the tabs are preferably not placed at the middle of any longitudinal edge to prevent matching up edges 30 in relationship opposite to correct relationship. It is understood, however, that the patterns allow margins of $\frac{3}{8}$ " to $\frac{1}{2}$ " at all seam edges for seaming operation.

It will also be understood that the indicating 35 tabs may either extend from the edges to be seamed or may be cut therefrom. Preferably, the tabs are stamped out before the usual cutting operation.

- While certain symbols or shaped tabs are used, 40 it will be understood that any suitable shaped tabs or notches may be used. Similar tabs are used only on edges to be seamed together and are not otherwise repeated.

It will be understood that all the pre-cut parts 45 may be packed in a suitable box and the cover of the box may be printed with a picture showing the completed garment. Also, the box may have a window in it through which the fabric of the parts may be seen. The cover may also be printed with suitable instructions, if desired.

Of course, the tabs may be cut in any suitable manner as by shears or cutting machines if desired. If desired numerical symbols may be used instead of tabs or instead of geometrical 55 symbols.

Although the parts A, A'; B, B'; D, D'; E; F, F'; and G, G'; are pre-cut cloth parts, it will be understood that these parts may be in the form of paper patterns which are to be placed on a piece of cloth which is to be cut, so that the cut cloth parts will have the tab extensions to facilitate matching up correctly edges to be seamed together.

65 It will thus be seen that there is provided a device in which the several objects of this invention are achieved and which is well adapted to meet the conditions of practical use.

As various possible embodiments might be made of the above invention, and as various changes might be made in the embodiment above set forth, it is to be understood that all matter herein set forth or shown in the accompanying drawings is to be interpreted as illustrative and not in a limiting sense.

Having thus described my invention I claim as new and desire to secure by Letters Patent:

A set of pre-cut patterned cloth pieces to be joined together to form a garment, one of said parts having an edge to be seamed to edges of two other parts, said edge of said part being provided with two different tab extensions of different shapes and each of said edges of said two other parts having a tab extension corresponding in shape to respective tab extensions on said one edge, to indicate that said one edge is to be stitched partly to one of said two other edges, and partly to the other of said two other edges, and said tabs on all of said edges being so positioned that proper portions of said two other edges will be aligned with the first edge when similar tabs are placed in registration, all single edges of parts to be seamed to single edges.

of other parts being provided with corresponding tab extensions, the tabs on each edge being so positioned that the edges will be properly oriented when the tabs are brought together, the corresponding tabs on each pair of single edges being different from tabs on all other edges.

LOUIS BECKER.
